C. H. McCARTY.
LATCH DEVICE FOR IRRIGATING DIVIDING BOXES.
APPLICATION FILED DEC. 23, 1913.

Patented Sept. 29, 1914.

Fig. 1.

UNITED STATES PATENT OFFICE.

CHARLES H. McCARTY, OF WELLINGTON, COLORADO.

LATCH DEVICE FOR IRRIGATING DIVIDING-BOXES.

1,111,914.

Specification of Letters Patent.

Patented Sept. 29, 1914.

Application filed December 23, 1913. Serial No. 808,516.

To all whom it may concern:

Be it known that I, CHARLES H. McCARTY, a citizen of the United States, residing at Wellington, in the county of Larimer 5 and State of Colorado, have invented a new and useful Latch Device for Irrigating Dividing-Boxes, of which the following is a specification.

The present invention appertains to a 10 latch or locking device applicable to irrigating dividing boxes, and operable to lock the dividing board or gate, at any adjusted position, whereby the flow or diversion of water into the lateral may be properly controlled.

It is the object of the present invention to provide a latch or locking device of the nature indicated, which shall be comparatively simple and inexpensive in construction, as 20 well as simple, practical and efficient in its use, the present device being of such construction, as not to interfere with the flow of the water along the irrigating main, or into the lateral.

It is also the object of the present invention to provide a device of the character specified, which may be readily applied to a 25 dividing box, to coöperate with the free end of the dividing board or gate, whereby the free end of the dividing board or gate may be locked at various adjusted positions, and whereby the free end of the gate or dividing board will also be guided in its swinging movements.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the 45 scope of what is claimed, without departing from the spirit of the invention.

The invention has been illustrated in its preferred embodiment in the accompanying drawing, wherein:

Figure 1 is a plan view of a dividing box of an irrigating main, illustrating the improved latch device applied. Fig. 2 is a longitudinal section of the dividing box, taken along the dividing board or gate.

In the drawings, the numeral 1 designates 55 an ordinary or prevailing type of dividing box, having the opening 2 in one side, for the admission of water from the main, in which the dividing box is disposed, into the lateral or irrigating ditch. The water flows 60 through the box in the direction of the arrow in Fig. 1. That side of the dividing box having the opening 2 is provided with a partition 3 projecting therefrom, and to which the dividing board or gate 4 is 65 hinged. The dividing board or gate 4 projects forwardly beyond the opening 2, and is adapted to be swung between the sides of the dividing box, for diverting the water from the main into the lateral, as is well 70 understood. The dividing board or gate 4 is also adapted to close the opening 2, when swung against the respective side of the dividing box, as illustrated in dotted lines in Fig. 1, so that the dividing board or gate 75 4 may either control the amount of water admitted into the lateral, or may shut off the supply of water to the lateral.

In carrying out the present invention, a break board or cleat 5 is secured to the 80 bottom of the dividing box 1 slightly in advance of the dividing board or gate 4, and is disposed transversely with its ends projecting to the sides of the dividing box. A strip or plate 6 is secured upon the break board 85 or cleat 5, and has its rear edge projecting beyond the said board or cleat, the rear or projecting end portion of the strip 6 being provided with a series of staggered apertures 7.

The free or forward end of the dividing board or gate 4 is arranged to move adjoining the rear edge of the strip 6, and an upright bar or strip 8 is secured to the free end of the dividing board, and has its lower 95 end bent angularly to provide a foot 9 working snugly under the free or rear edge of the retaining or guide strip 6, to assist in guiding the dividing board or gate 4 for swinging movements. The foot or angular 100 end 9 of the strip 8 is provided with a slot 10 adapted to successively register with the longitudinal series of staggered apertures 7 of the plate or strip 6, when the gate or dividing board is swung.

A strip or bar 11 is disposed above the plate or strip 6, and has one end connected loosely to that side of the dividing box 1,

having the opening 2, preferably by means of an eye bolt 12 engaging through the said side of the dividing box. The strip 11 is provided with a longitudinal series of staggered apertures 13, corresponding with the apertures 7 of the plate or strip 6.

A strip or leaf 14 is secured upon the upper edge of the dividing board or gate 4, and projects beyond the free end thereof, 10 the locking strip 11 being adapted to rest upon the protruding portion of the strip or leaf 14, said protruding portion of the strip or leaf 14 having a slot 15 corresponding with the slot 10 of the foot or angular end 9 15 of the strip 8 secured to the free end of the dividing board or gate.

A latch bolt 16 is insertible through the alining apertures of the strips 11 and 6, and through the slots 15 and 10 of the parts 14 20 and 9, respectively, whereby the dividing board or gate may be locked at various angular positions. The upper end of the latch bolt 16 is preferably headed, for convenience in handling the same.

25 Means is provided for locking the latch bolt in position, and to this end, the free end of the strip or leaf 14 is bent angularly upward, as at 17, and has hinged thereto, a hasp 18 provided with the slot 19 adapted 30 to swing over a keeper 20 carried by basal or butt end portion of the strip or leaf 14, whereby a shackle lock, or the like, may be engaged through the keeper 20 to lock the hasp 18 over the latch bolt 16, whereby the 35 latch bolt may not be withdrawn by malicious or unwarranted persons.

In practice, the latch mechanism may be readily applied to the dividing box, and to either side of various dividing boxes, according to the position of the dividing boards or gates. When the hasp 18 is swung open or upward, the latch bolt 16 may readily be withdrawn upwardly, so that the dividing board or gate may be swung to the 45 position desired, the slots 15 and 10 of the parts 14 and 9 carried by the free end of the gate, successively registering with the apertures 13 and 7 of the strips 11 and 6, whereby when the gate has been properly positioned, the latch bolt may be dropped through the proper aperture 13, to engage 50 through the slot 15, the lower alining aperture 7, and the slot 10. In this manner, the gate is locked against swinging movement, and by swinging the hasp 18 over the keeper 20, and locking the hasp in position, as above intimated, the gate or dividing board cannot be reset by unauthorized or malicious persons. The water may thus 55 be properly diverted from the main into the lateral or, the gate or dividing board may be closed, to prevent the flow of water into the lateral.

The advantages of a device of the pres-

ent character will be obvious to those versed 65 in the art, without further comment, it being observed that the objects aimed at have been carried out satisfactorily by the provision of the latch device above described.

Having thus described the invention, what 70 is claimed as new is:—

1. The combination with a dividing box, and a hinged dividing board therein, of a transverse strip disposed between the sides of the dividing box adjoining the free end of 75 the dividing board, a member carried by the free end of the dividing board and coöperable with the said strip, and locking means engageable with the said strip at various points along its length and with the said 80 member.

2. The combination with a dividing box, and a hinged dividing board therein, of a transverse apertured strip disposed within the dividing box adjoining the free end of 85 the dividing board, a member secured to the free end of the dividing board and having a protruding slotted portion coöperating with the said strip, and a locking member insertible through the apertures of the said strip 90 and the slot of the said member.

3. The combination with a dividing box, and a hinged dividing board therein, of an apertured strip attached to one side of the dividing box and extending transversely adjoining the free end of the dividing board, a member carried by the free end of the dividing board and coöperable with the said strip, a latch bolt insertible through the said strip and member, and means carried by the 100 dividing board and arranged to be locked over the latch bolt to prevent its withdrawal.

4. The combination with a dividing box, and a dividing board therein, of a transverse apertured strip supported within the dividing box at the free end of the dividing board, a strip attached to the free end of the dividing board and projecting therefrom, the projecting portion of the second mentioned strip having a slot coöperating with the apertures 110 of the first mentioned strip, a latch bolt insertible through the said strips, a hasp hinged to the free end of the second mentioned strip and adapted to swing over the latch bolt, and a keeper carried by the dividing 115 board for coöperation with the hasp.

5. The combination with a dividing box, and a hinged dividing board therein, of an apertured strip connected loosely to one side of the dividing box and arranged to be disposed adjoining the free end of the dividing board, a leaf secured to the upper edge of the dividing board and projecting from the free end of the said board, the projecting portion of the leaf having a slot, the said strip being adapted to rest upon the projecting portion of the leaf to coöperate with the 120 said slot, a keeper carried by the basal por-

tion of the said leaf, a latch bolt insertible through the said apertured strip and slotted portion of the said leaf, and a hasp hinged to the free end of the said leaf to swing over 5 the latch bolt, and having a slot to engage over the keeper.

In testimony that I claim the foregoing

as my own, I have hereto affixed my signature in the presence of two witnesses.

CHARLES H. McCARTY.
